TELEVISION SCANNING DISK

Kurt Heinz Graefe, Berlin, Germany, assignor
to Radioaktiengesellschaft D. S. Loewe, Berlin-Steglitz, Germany, a company of Germany

Application March 7, 1938, Serial No. 194,359
In Germany March 8, 1937

3 Claims. (Cl. 178—7.6)

The present invention relates to television scanning disks and more particularly to disks upon which, in order to avoid the so-called key-
stone distortion, the scanning light bundle falls
at an inclined angle.

If the scanning holes of the disk are punched as usual in the form of circles, squares or other regular polygons the oblique passage of the light causes some disadvantages which will be explained later on.

It is an object of the invention to avoid these disadvantages by forming the holes in a special way.

Further objects of the invention may be best understood by reference to the following description taken in connection with the accompanying drawing in which

Fig. 1 is a side view of a scanning disk as used hitherto and of the oblique light ray whilst
Figs. 2 to 4 show different embodiments of the invention.

Figs. 2a, 3a and 4a in cross-section.

Figs. 2b and 2c, 3b and 4b in front view.

In Fig. 1 11 is the scanning disk provided with holes 12 through which the bundle of light 15, after having traversed film 14 and lens 13, passes at an angle α . Consequently the useful cross-section of the hole for the bundle is reduced by the factor $\cos \alpha$, if the thickness of the disk is zero, and still more if the thickness is of the same order of magnitude as the diameter of the hole.

A further disadvantage when employing inclined incidence of the light is an increased danger of contamination which makes itself noticeable in such form that holes which when viewed under the microscope appear completely clear cause upon inclined passage of the light a light dissipation of more than 50% owing to opaque scales which cover up a part of the inside.

Fig. 2 shows how this danger is overcome according to the invention. The holes are punched out, not of the disk 11 itself, but of thin sheets 22, preferably of copper foil, covering larger holes of the disk. The thickness of the sheets may be approximately equal to the diameter of the holes.

The cross-section of the holes 12 is made, in order to obtain a circular or square cross-section of the light bundle, elliptic (Fig. 2c) resp. rectangular (Fig. 2b). The proportion of width to length of these cross-sections had to be $\cos \alpha$, if the thickness of the sheets 22 were zero, and has to be still less as the thickness is relatively considerable.

Another method to obtain practically the same result shows Fig. 3, for example for a circular hole. The hole 12 is produced by a punch, which encloses together with the plane of the disk the same angle α for which provision is made in respect of the subsequent ray of light.

The inclined punching of a precise hole in metal foil is, however, accompanied by the danger of the punch slipping, so that the hole gets inaccurate in its position. This disadvantage can only be overcome by very precise guiding of the punch.

The two inventive ideas of Fig. 2 and Fig. 3 may also be combined according to Fig. 4. In order to obtain a square bundle of light a rectangular hole is punched obliquely at an angle α .

I claim:

1. In the television art a scanning disk which is traversed by the scanning light bundle at an oblique angle having scanning holes the projection of which onto a plane perpendicular to said light bundle is a regular polygon.

2. In the television art a scanning disk which is traversed by the scanning light bundle at an oblique angle having scanning holes the projection of which onto a plane perpendicular to said light bundle is a regular polygon, said holes being punched out of sheets of a thickness about equal to the diameter of the holes, said sheets covering larger holes in said disk.

3. In the television art a scanning disk which is traversed by the scanning light bundle at an oblique angle having scanning holes the projection of which onto a plane perpendicular to said light bundle is a regular polygon and the walls of which are parallel to said light bundle.

KURT HEINZ GRAEFE.
